[57] ABSTRACT

An ultrasonic delay line which comprises a solid body and two input and output electro-mechanical transducers for converting electrical energy into ultrasonic mechanical energy or vice versa, and in which the ultrasonic wave, emitted from the input electro-mechanical transducer by the application of an electric input signal thereto, is reflected by at least one reflecting surface formed in the solid body and enters the output electro-mechanical transducer to derive therefrom an electric output signal which is delayed behind the electric input signal for a period of time during which the ultrasonic wave propagates in the solid body. The reflecting surface has at least one elliptical surface whose focuses are located each at one point on each electro-mechanical transducer or its equivalent point.

1
ULTRASONIC DELAY LINE

BACKGROUND OF THE INVENTION

1. Field of the Invention

This invention relates to an ultrasonic delay line which comprises a solid body for propagation of ultrasonic mechanical energy therein, and two input and output electro-mechanical transducers (or a single combined input and output electro-mechanical transducer) for converting electrical energy into ultrasonic mechanical energy or vice versa, and in which the ultrasonic wave, emitted from the input electro-mechanical transducer (or the combined input and output electro-mechanical transducer) by the application of an electric input signal thereto, propagates in the solid body and is reflected by at least one reflecting surface formed in the solid body and enters the output electro-mechanical transducer (or the combined input and output electro-mechanical transducer) to derive therefrom an electric output signal which is delayed behind the electric input signal for a period of time during which the ultrasonic wave propagates in the solid body.

2. Description of the Prior Art

In conventional ultrasonic delay lines of this type (which will be described on the assumption that they have an input and an output electromechanical transducer, for the sake of brevity), the ultrasonic wave emanating from the input electro-mechanical transducer gradually spreads as it goes away from the transducer. Consequently, the distance of propagation of the ultrasonic wave passing the center of the spreading differs from those of the ultrasonic waves deviating away from the center, so that no exactly defined delay time can be obtained between the electric input and output signals, the electric output signal becomes distorted and, further, an excellent frequency or phase characteristic cannot be obtained as a whole.

To avoid such defects experienced in the prior art, an ultrasonic delay line of the following construction has been proposed. Namely, a solid body is formed in the shape of a solid plate which has parallel, opposing first and second major surfaces, first and second transducer mounting side surfaces perpendicular to the first and second major surfaces and extending in a straight line when viewed from the sides of the first and second major surfaces, and at least one reflecting surface perpendicular to the first and second major surfaces. An input electro-mechanical transducer is mounted on the first mounting side surface and polarized parallel to the first and second major surfaces and the first mounting side surface so that the ultrasonic wave from the input electromechanical transducer may be emitted in a direction normal to the first mounting side surface as a whole. An output electro-mechanical transducer is mounted on the second transducer mounting side surface and polarized parallel to the first and second major surfaces and the second mounting side surface. The output transducer is adapted to provide a maximum electric output signal when the ultrasonic wave incident on the transducer is perpendicular to the second mounting side surface as a whole. For this purpose, it is arranged that the ultrasonic wave emitted from the input electro-mechanical transducer into the solid plate and spreading in the direction of the thickness of the solid plate is reflected by the first and second major

surfaces, thereby to prevent unnecessary spreading of the ultrasonic wave in the direction of the thickness of the solid plate.

In this case, the first and second major surfaces and

- 5 the reflecting surface are arranged relative to each other so that the ultrasonic wave emitted from the input electro-mechanical transducer at right angles to the first transducer mounting side surface and passing its center corresponding to the effective one of the
10 input electro-mechanical transducer, viewed from the sides of the first and second major surfaces, is reflected at the center of the reflecting surface viewed from the sides of the first and second major surfaces and passes through the second transducer mounting side surface at its center corresponding to the effective center of the
15 output electro-mechanical transducer viewed from the sides of the first and second major surfaces and perpendicularly to the mounting side surface and then strikes the output electro-mechanical transducer. Further,
20 there are provided on the first and second major surfaces ultrasonic wave absorbing members which are spaced a predetermined distance apart from and extend parallel to the center of the path of the ultrasonic
25 wave which emanates from the input electro-mechanical transducer and gradually spreads as it goes away therefrom. Accordingly, those ultrasonic waves which have spread in the direction of the surface dimension of the solid plate are absorbed by the ultrasonic
30 wave absorbing members, thereby preventing that the ultrasonic waves having unnecessarily spread out from the path in the direction of the surface dimension of the solid plate strike the output electro-mechanical transducer.
- 35 In such a conventional ultrasonic delay line, however, since the ultrasonic wave spreading out in the direction of the surface dimension of the solid plate is absorbed by the absorbing members, only one part of the ultrasonic wave emitted from the input electro-
40 mechanical transducer reaches the output electro-mechanical transducer, and accordingly the resulting transmission loss between the electric input and output signals is appreciably great. Further, the use of the ultrasonic wave absorbing members naturally necessi-
45 tates a process for mounting them on the first and sec-
ond major surfaces of the solid plate. Moreover, in ad-
dition to the ultrasonic wave passing the center of the ultrasonic wave path, the ultrasonic wave spreading be-
50 tween the center of the path and the inner side of the ultrasonic wave absorbing member disposed close to the output electro-mechanical transducer enters the output transducer, so that an exactly defined delay time cannot be obtained, the electric output signal is dis-
55 torted and an excellent frequency or phase characteris-
tic cannot be obtained.

SUMMARY OF THE INVENTION

Accordingly, one object of this invention is to pro-
60 vide an ultrasonic delay line which is designed so that even if the ultrasonic wave emitted from an input elec-
tro-mechanical transducer (or a combined input and output electro-mechanical transducer) spreads as it goes away therefrom, an exactly defined delay time can be omitted between electric input and output signals, the electric output signal does not become distorted and an excellent frequency or phase characteristic can be obtained.

Another object of this invention is to provide an ultrasonic delay line which employs a solid plate as in the conventional ultrasonic delay line but provides the abovementioned excellent features without mounting any ultrasonic wave absorbing members on the solid plate and which is small in transmission loss between electric input and output signals.

Other objects, features and advantages of this invention will become apparent from the following description taken in conjunction with the accompanying drawings.

BRIEF DESCRIPTION OF THE DRAWINGS

FIGS. 1A and 1B are plan and front views respectively illustrating one example of an ultrasonic delay line according to this invention;

FIGS. 2 to 9 respectively show other examples of this invention;

FIGS. 10 to 18 respectively show other examples of this invention;

FIGS. 19A and 19B are plan and front views illustrating another example of this invention; and

FIGS. 20 to 26 respectively illustrate other examples of this invention.

DESCRIPTION OF THE PREFERRED EMBODIMENTS

FIG. 1 illustrates a first embodiment of this invention, which comprises a solid plate 1 for propagation of ultrasonic mechanical energy therethrough and input and output electro-mechanical transducers 2 and 2' for converting electrical energy into ultrasonic mechanical energy or vice versa.

The solid plate 1 may be formed of, for example, glass, elinvar, ceramics or like known material. The solid plate 1 has parallel, opposing first and second major surfaces 3a and 3b, first and second transducer mounting side surfaces 4 and 4' normal to the major surfaces 3a and 3b and extending in a straight line when viewed from the sides of the major surfaces, and a reflecting surface D₁ normal to the major surfaces 3a and 3b. In this case, the distance between the first and second major surfaces 3a and 3b, that is, the thickness of the solid plate 1 is selected as relatively small as 0.5 to 5 times the wavelength of the ultrasonic wave emanating from the input electro-mechanical transducer 2, as will be described hereinbelow. The reason why the thickness of the solid plate 1 is selected to be 0.5 to 5 times the wavelength of the ultrasonic wave is that when it is less than 0.5 times, the mechanical strength of the solid plate 1 is insufficient and that when it is less than 5 times, even if the ultrasonic wave slightly spreads in the thickness dimension of the plate, it is immediately reflected by the first and second major surface 3a and 3b and is thereby caused to propagate in the solid plate 1 substantially parallel to the major surfaces 3a and 3b.

The transducers 2 and 2' may be any known ones but have the shape of a plate as a whole and they are respectively mounted on the transducer mounting side surfaces 4 and 4' through an adhesive binder, though not shown. In this case, the transducer 2 is polarized parallel to the major surfaces 3a and 3b and the mounting side surface 4, while the transducer 2' is similarly polarized parallel to the major surfaces 3a and 3b and the mounting side surface 4'. These transducers 2 and 2' are of such a size that the ultrasonic wave emanating

from the transducers can be equivalently obtained from the centers on the mounting side surfaces corresponding to the effective centers of the transducers viewed from the sides of the major surfaces 3a and 3b. Consequently, the ultrasonic wave, which is emitted from the central point P₀ on the mounting side surface 4 viewed from the sides of the major surfaces 3a and 3b, corresponding to the effective central point on the transducer 4, by the application of an electric input signal 10 to the transducer 4 through an input terminal (not shown) led out therefrom, gradually spreads as it goes away from the point P₀ but, as a whole, it is effectively emitted perpendicular to the side surface 4. While, an electric output signal, which is derived from an output terminal (not shown) led out from the transducer 2', becomes maximum when the ultrasonic wave enters, perpendicular to the side surface 4', the central point P₀' on the side surface 4' viewed from the sides of the major surfaces 3a and 3b, corresponding to the effective central point on the transducer 2'.

The aforementioned transducer mounting side surfaces 4 and 4' and the reflecting surface D₁ are arranged relative to each other in such a manner that the ultrasonic wave, emitted from the transducer 2 at the point P₀ perpendicularly to the side surface 4, propagates in the solid plate 1 and is reflected at the central point P₁ on the reflecting surface D₁ viewed from the sides of the major surfaces 3a and 3b and enters the transducer 2' at the point P₀' perpendicularly to the side surface 4'. The ultrasonic wave passing the line joining P₀, P₁ and P₀' will hereinafter be referred to as a central ultrasonic wave and indicated by 5P. In this case, the reflecting surface D₁ is opposed to the transducer mounting side surfaces 4 and 4' and lies in a plane extending along an elliptic line passing the point P₁ with the points P₀ and P₀' being used as focuses, when viewed from the major surfaces 3a and 3b.

With such an arrangement as described above, the ultrasonic wave emitted from the transducer 2 at the point P₀ towards the reflecting surface D₁ and spreading in the direction of thickness of the solid plate 1 is reflected by the major surfaces 3a and 3b and it is regarded as substantially parallel to the major surfaces 3a and 3b, since the solid plate 1 is relatively thin. On the other hand, the ultrasonic waves, which spread along maximum spreading paths 5a and 5b on both sides of the central ultrasonic wave path 5P as they go away from the point P₀, are reflected at point a₁ and b₁ on the reflecting surface D₁ on both sides of the point P₁ respectively. In this case, the points a₁ and b₁ lie on the elliptic line passing the point P₁ with the points P₀ and P₀' being used as focuses, so that the path 5a connects the points P₀, a₁ and P₀' and hence becomes complete, while the path 5b connects the points P₀, b₁ and P₀' and hence similarly becomes complete. The paths 5a and 5b are equal in length to that 5P.

Accordingly, if the eccentricity of the above elliptic line is predetermined in accordance with a desired delay time of the electric output relative to the electric input signal, substantially almost all of the ultrasonic wave emitted from the input transducer 2 strikes the output transducer 2', even if it spreads as it goes away from the transducer 2, so that it is possible to obtain the function of an ultrasonic delay line which is small in transmission loss between the electric input and output signals. Of course, all the ultrasonic paths to the transducer 2' are equal in length, so that an exactly defined

delay time can be obtained, the electric output signal does not become distorted and an excellent frequency or phase characteristic can be obtained as a whole.

FIG. 2 shows a second embodiment of this invention, in which parts corresponding to those in FIG. 1 are marked with the same reference numerals and characters. The reflecting surface is composed of two surfaces D_1 and D_2 . The transducer mounting side surfaces 4 and $4'$ and the reflecting surfaces D_1 and D_2 are disposed relative to each other in such a manner that the ultrasonic wave emitted from the input transducer 2 at the point P_0 perpendicularly to the side surface 4 propagates in the solid plate 1 and is reflected at the central point P_1 on the reflecting surface D_1 and then reflected at the central point P_2 on the reflecting surface D_2 and strikes the output transducer $2'$ at the point P_0' . In this case, the reflecting surface D_2 is a straight line surface which extends along a straight line passing the point P_2 and extending normal to a bisector of an angle formed between a line connecting the points P_1 and P_2 and that connecting the points P_2 and P_0' . On the other hand, the reflecting surface D_1 is opposed to the side surface 4 and the reflecting surface D_2 and it is an elliptic surface which, if an equivalent central point $P_0'-1$ symmetrical with the point P_0' with respect to an imaginary plane M_2 including the surface D_2 is considered, extends along an elliptic line using the points P_0 and $P_0'-1$ as focuses and passing the point P_1 .

With the above construction of the second embodiment, the path 5P of the ultrasonic wave emanating from the input transducer 2 connects the points P_0 , P_1 , P_2 and P_0' and becomes complete, while the paths 5a and 5b respectively connect P_0 , points a_1 and b_1 on the reflecting surface D_1 on both sides of the point P_1 , points a_2 and b_2 on the reflecting surface D_2 on both sides of the point P_2 and the point P_0' and become complete, because the points a_1 and b_1 on the reflecting surface D_1 lie on the elliptic line using as its focuses the points P_0 and $P_0'-1$ equivalent to the point P_0' and passing the point P_1 and because the point a_2 and b_2 on the reflecting surface D_2 lie on the straight line including the point P_2 and extending perpendicular to the bisector of the angle between the line connecting the points P_1 and P_2 and that connecting the points P_2 and P_0' . The paths 5a and 5b are equal in length to that 5P. Accordingly, it is possible to obtain the same excellent results as those obtainable with the embodiment of FIG. 1.

FIG. 3 illustrates a third embodiment of this invention, in which parts corresponding to those in FIG. 2 are identified by the same reference numerals and characters and no detailed description will be repeated. This embodiment is identical in construction with that of FIG. 2 except that the transducer mounting side surfaces 4 and $4'$ and the reflecting surfaces D_1 and D_2 are arranged relative to another in such a manner that the ultrasonic wave may cross itself in the solid plate 1. This embodiment provides the same results as those obtainable with the embodiment of FIG. 2 and a long delay time.

FIG. 4 shows a fourth embodiment of this invention, in which parts corresponding to those in FIG. 1 are designated by the same reference numerals and characters and of which no detailed description will be given. This embodiment employs three reflecting surfaces D_1 , D_2 and D_3 . The transducer mounting side surfaces 4 and $4'$ and the reflecting surfaces D_1 to D_3 are positioned

relative to one another such that the ultrasonic wave, emitted from the output transducer 2 at the point P_0 perpendicularly to the side surface 4, is successively reflected at the central points P_1 , P_2 and P_3 on the reflecting surfaces D_1 , D_2 and D_3 before striking the output transducer $2'$ at the point P_0' perpendicular to the side surface $4'$. In this case, the reflecting surface D_1 is a surface extending along a straight line including the point P_1 and normal to the bisector of the angle between a line connecting the points P_0 and P_1 and that connecting the points P_1 and P_2 . The reflecting surface D_3 is a surface extending along a straight line including the point P_3 and extending perpendicular to the bisector of the angle between a line connecting the points P_2 and P_3 and that connecting the points P_3 and P_0' . On the other hand, the reflecting surface D_2 is a surface that includes an elliptic line including the point P_2 and using as its focuses an equivalent central point $P_0'-1$ symmetrical with the point P_0' with respect to an imaginary plane M_1 including the surface D_1 and an equivalent central point $P_0'-1$ symmetrical with the point P_0' with respect to an imaginary plane M_3 including the surface D_3 .

With such an arrangement as described above, the same results as those obtainable with the foregoing examples can be obtained, as will be seen from the foregoing, so that no detailed description will be made in this connection. The path 5P is formed with straight lines connecting the points P_0 , P_1 , P_2 , P_3 and P_0' ; the path 5a is formed with straight lines interconnecting the points P_0 , a_1 , a_2 and a_3 on the reflecting surfaces D_1 , D_2 and D_3 and P_0' ; the path 5b is formed with straight lines interconnecting the points P_0 , b_1 , b_2 and a_3 on the reflecting surfaces D_1 , D_2 and D_3 and P_0' ; and the paths 5a and 5b are equal in length to the path 5P, so that it is possible to obtain the same results as those obtainable with the foregoing embodiments.

FIG. 5 shows a modified form of the ultrasonic delay line of FIG. 4 which is identical in construction with that of FIG. 4 except that the transducers 4 and $4'$ and the reflecting surfaces D_1 to D_3 are positioned relative to one another so that the ultrasonic wave may cross itself in the solid plate 1. Hence, no detailed description will be repeated but this embodiment provides the same results as those obtainable with the embodiment of FIG. 4 and a long delay time.

FIG. 6 illustrates another modification of the ultrasonic delay lines of FIGS. 4 and 5, which is identical in construction with the latter except that the reflecting surface D_2 lies in a plane extending along a straight line passing the point P_2 and extending perpendicular to the bisector of the angle between a line connecting the points P_1 and P_2 and that connecting the points P_2 and P_3 , that the reflecting surface D_3 lies in a plane extending along a straight line passing the point P_3 and extending perpendicular to the bisector of the angle between a line connecting the points P_2 and P_3 and that connecting the points P_3 and P_0' , and that the reflecting surface D_1 extends along an elliptic line whose focuses, if an equivalent point $P_0'-1$ and an imaginary plane M_3-1 symmetrical with the point P_0' and the reflecting surface D_3 with respect to an imaginary plane M_2 including the surface D_2 and an equivalent point $P_0'-2$ symmetrical with the point $P_0'-2$ with respect to the imaginary plane M_3-1 are considered, are selected at the point P_0 and the point $P_0'-2$ and which passes the point P_1 . This

embodiment also provides the same results as those obtainable with the embodiments of FIGS. 4 and 5.

FIG. 7 shows a seventh embodiment of this invention which employs four reflecting surfaces D_1 to D_4 and in which the reflecting surface D_1 is similar to that D_1 employed, for example, in the embodiment of FIG. 4, the reflecting surfaces D_3 and D_4 are similar to those D_2 and D_3 used in the embodiment of FIG. 6 and the reflecting surface D_2 extends along an elliptic line whose focuses are at an equivalent central point P_0-1 similar to that in FIG. 4 and an equivalent central point $P_0'-2$ similar to that in FIG. 6 and which passes the point P_2 . Accordingly, this embodiment also provides the same results as those obtainable with the foregoing embodiments.

FIG. 8 illustrates a modified form of the ultrasonic delay line of FIG. 7, which is identical in construction therewith except that the transducer mounting side surface and the reflecting surfaces are so arranged that the ultrasonic wave may cross itself in the solid plate. This embodiment also provides the same results as those obtainable with the foregoing embodiment.

FIG. 9 shows a ninth embodiment of this invention which employs five reflecting surfaces D_1 to D_5 . In this embodiment, the reflecting surfaces D_1 , D_2 , D_4 and D_5 are formed to lie in planes extending straight lines in the manners described previously and the surface D_3 is formed to lie extends along an elliptic line in the manner described above. The same results as those obtainable with the foregoing embodiments can be obtained. Further, the number of the reflecting surfaces is odd as in the embodiment of FIG. 5 and if that number is taken as n , the $[(n+1)/2]$ th surface from the side of the side surface 4, that is, the intermediate surface, is elliptic, so that the reflecting surfaces can be positioned symmetrical with respect to a line normal to that connecting the transducers 2 and $2'$. This facilitates the fabrication of the ultrasonic delay line and provides a long delay time.

FIG. 10 illustrates a tenth embodiment of this invention which corresponds to the foregoing first one and in which parts corresponding to those in FIG. 1 are indicated by the same reference numerals and characters and of which no detailed description will be given. In this embodiment, the transducer 2 and $2'$ are each of such a size that the ultrasonic wave is emitted from the transducer 2 or $2'$ to the full width between both side points on the mounting side surface 4 or $4'$ corresponding to effective side points of the transducer, viewed from the major surfaces $3a$ and $3b$. Consequently, the ultrasonic wave, which is emitted from the area on the side surface 4 between the side points a_0 and b_0 corresponding to the effective ones of the transducer 2, gradually spreads as it goes away from the areas defined between the both side points a_0 and b_0 . The transducer mounting side surfaces 4 and $4'$ and the reflecting surface D_1 are arranged relative to one another so that the ultrasonic waves, emitted from the transducer 2 and passing the points P_0 , a_0 and b_0 perpendicularly to the side surface 4, are respectively reflected at the central point P_1 and points c_1 and d_1 on the both sides thereof on the reflecting surface D_1 , viewed from the major surfaces $3a$ and $3b$, and enter the output transducer $2'$ passing through the point P_0' and those a_0' and b_0' on the both sides thereof perpendicularly to the side surface $4'$ and that the respective ultrasonic wave paths indicated by $5P$, $5c$ and $5d$ may be equal in length to

one another. Further, the reflecting surface D_1 comprises a linear area d_p extending along a straight line connecting points c_2 and d_1 and first and second elliptic areas d_a and d_b continuously extending outwardly of the linear area d_p on the both sides thereof respectively. In this case, the linear area d_p lies in plane extending along the straight line connecting the points c_1 and d_1 when viewed from the major surfaces $3a$ and $3b$ but this straight line passes the point P_1 , since the path passing the points P_0 , P_1 and P_0' is equal in length to those passing a_0 , c_1 and a_0' and b_0 , d_1 and b_0' . The elliptic area d_a extends along an elliptic line whose focuses are selected at the points a_0 and a_0' when viewed from the sides of the major surfaces $3a$ and $3b$. While, the elliptic area d_b extends along an elliptic line whose focuses are selected at the points b_0 and b_0' .

With such an arrangement as described above, the ultrasonic wave emitted from the transducer 2 through the area between the points a_0 and b_0 towards the reflecting surface D_1 and spreading in the direction of thickness of the solid plate 1 is reflected by the major surfaces $3a$ and $3b$ as in the case of FIG. 1, so that it is regarded as substantially parallel to the major surfaces $3a$ and $3b$. On the other hand, the ultrasonic waves, which spread along maximum spreading paths $5a$ and $5b$ outwardly of the ultrasonic wave paths $5c$ and $5d$ are reflected at outer points a_1 and b_1 on the elliptic areas d_a and d_b of the reflecting surface D_1 respectively. In this case, the point a_1 lies on the elliptic line whose focuses are at the points a_0 and a_0' and which passes the point a_1 and the points b_1 lies on the elliptic line whose focuses are at the points b_0 and b_0' and which passes the point b_1 , so that the path $5a$ connects the points a_0 , a_1 and a_0' and hence becomes complete, while the path $5b$ connects the points a_0 , b_1 and a_0' and hence similarly becomes complete. The paths $5a$ and $5b$ are equal in length to those $5P$, $5c$ and $5d$.

Accordingly, it is possible to obtain the function of delay means which provides an exactly defined delay time and an excellent characteristic.

FIG. 11 shows an eleventh embodiment of this invention, in which parts corresponding to those in FIG. 10 are marked with the same reference numerals and characters. The reflecting surface is composed of two surfaces D_1 and D_2 . The transducer mounting side surfaces 4 and $4'$ and the reflecting surfaces D_1 and D_2 are disposed relative to each other in such a manner that the ultrasonic waves emitted from the input transducer 2 at the points P_0 , a_0 and b_0 perpendicularly to the side surface 4 propagates in the solid plate 1 along the paths $5P$, $5c$ and $5d$ of the same length and are reflected at the points P_1 , c_1 and d_1 on the reflecting surface D_1 and then reflected again at the points P_2 , c_2 and d_2 on the reflecting surface D_2 and strike the output transducer $2'$ at the points P_0' , a_0' and b_0' perpendicularly to the side surface $4'$. In this case, the reflecting surface D_2 is a straight line surface which extends along a straight line passing the points P_2 , c_2 and d_2 and extending normal to a bisector of an angle formed between a line connecting the points P_1 and P_2 and that connecting the points P_2 and P_0' . On the other hand, the reflecting surface D_1 is opposed to the side surface 4 and the reflecting surface D_2 and it is an elliptic surface comprising a straight-line area d_p connecting the points c_1 and d_1 and elliptic areas d_a and d_b extending outwardly of the area d_p . The elliptic areas d_a extends along an elliptic line whose focuses, if equivalent points P_0-1 , a_0-1 and

$b_0' - 1$ symmetrical with the points P_0' , a_0' and b_0' with respect to an imaginary plane M_2 including the surface D_1 are considered, are selected at the points a_0 and $a_0' - 1$ and which starts from the point c_1 . The elliptic area d_b extends along an elliptic line whose focuses are at the points b_0 and $b_0' - 1$ and which starts from the point d_1 .

With the above construction of the eleventh embodiment, the ultrasonic waves spreading along the paths $5a$ and $5b$ to maximum also strike the output transducer $2'$, so that it is possible to obtain the same excellent results as those obtainable with the embodiment of FIG. 10.

FIG. 12 illustrates a twelfth embodiment of this invention, in which parts corresponding to those in FIG. 11 are identified by the same reference numerals and characters and no detailed description will be repeated. This embodiment is identical in construction with that of FIG. 11 except that the transducer mounting side surfaces 4 and $4'$ and the reflecting surfaces D_1 and D_2 are arranged relative to one another in such a manner that the ultrasonic wave may cross itself in the solid plate 1. This embodiment provides the same results as those obtainable with the embodiment of FIG. 11 and a long delay time.

FIG. 13 shows a thirteenth embodiment of this invention, in which parts corresponding to those in FIG. 10 are designated by the same reference numerals and characters and of which no detailed description will be given. This embodiment employs three reflecting surfaces D_1 , D_2 and D_3 . The reflecting surfaces D_1 and D_3 lie in planes extending along straight lines and the reflecting surface D_1 comprises a straight-line area d_p and elliptic areas d_a and d_b .

With such an arrangement as described above, the same results as those obtainable with the foregoing examples can be obtained, as will be seen from the foregoing, so that no detailed description will be made in this connection.

FIG. 14 shows a modified form of the ultrasonic delay line of FIG. 13 which is identical in construction with that of FIG. 13 except that the transducers 4 and $4'$ and the reflecting surfaces D_1 and D_3 are positioned relative to one another so that the ultrasonic wave may cross itself in the solid plate 1. Hence, no detailed description will be repeated but this embodiment provides the same results as those obtainable with the embodiment of FIG. 13 and a long delay time.

FIG. 15 illustrates another modification of the ultrasonic delay lines of FIGS. 13 and 14, which is identical in construction with the latter except that the reflecting surfaces D_2 and D_3 respectively lie in planes extending along straight lines and that the reflecting surface D_1 comprises a straight-line area and an elliptic area. This embodiment also provides the same results as those obtainable with the embodiments of FIGS. 13 and 14.

FIG. 16 shows a sixteenth embodiment of the invention which employs four reflecting surfaces D_1 to D_4 and in which the reflecting surfaces D_3 and D_4 are straight and the reflecting surface D_2 comprises a straight-line area and an elliptic area. This embodiment also provides the same results as those obtainable with the foregoing embodiments.

FIG. 17 illustrates a modified form of the ultrasonic delay line of FIG. 16, which is identical in construction therewith except that the transducer mounting side surfaces and the reflecting surfaces are so arranged that

the ultrasonic wave may cross itself in the solid plate. This embodiment also provides the same results as those obtainable with the foregoing embodiment.

FIG. 18 shows an eighteenth embodiment of this invention which employs five reflecting surfaces D_1 to D_5 . In this embodiment, the reflecting surfaces D_1 , D_2 , D_4 and D_5 are formed to lie in planes extending straight lines in the manners described previously and the surface D_3 is formed to comprise a straight-line area and an elliptic area in the manner described above. The same results as those obtainable with the foregoing embodiments can be obtained. Further, the number of the reflecting surfaces is odd as in the embodiment of FIG. 14, so that the reflecting surfaces can be positioned symmetrical with respect to a line normal to that connecting the transducers 2 and $2'$ as described previously with regard to FIG. 9. This facilitates the fabrication of the ultrasonic delay line and provides a long delay time.

FIG. 19 shows another embodiment of this invention, which has three reflecting surfaces D_1 , D_2 and D_3 as in the foregoing embodiment of FIG. 5, in which parts corresponding to those in FIG. 5 are identified by the same reference numerals and characters and of which no detailed description will be given. In the present embodiment, the reflecting surface D_2 lies in a linear plane extending across the central point P_2 on the reflecting surface D_2 , when viewed from the sides of the major surfaces $3a$ and $3b$; the reflecting surface D_1 extends along an elliptic line whose focuses are selected at the central points P_0 and P_2 and which extends across the central point P_1 , when viewed from the sides of the major surfaces $3a$ and $3b$; and the reflecting surface D_3 extends along an elliptic line whose focuses are similarly selected at the central points P_2 and P_0' and which extends across the central point P_3 .

With the above construction of the nineteenth embodiment, the ultrasonic wave emitted from the transducer 2 at the point P_0 towards the reflecting surface D_1 and spreading in the direction of the thickness of the solid plate 1 is reflected by the major surfaces $3a$ and $3b$ as in the foregoing examples and it is regarded as substantially parallel to the major surfaces $3a$ and $3b$. On the other hand, the ultrasonic waves, which spread along maximum spreading paths $5a$ and $5b$ on both sides of the central ultrasonic wave path $5P$ as they go away from the point P_0 , are reflected at points a_1 and b_1 on the reflecting surface D_1 on both sides of the point P_1 respectively. In this case, the points a_1 and b_1 lie on the elliptic line whose focuses are at the points P_0 and P_2 and which passes the point P_1 , so that the ultrasonic waves are reflected at the reflecting surface D_1 and both centered on the point P_2 and reflected at this point. Then, the ultrasonic waves thus reflected at the point P_2 are reflected again at points a_3 and b_3 on the reflecting surface D_3 on both sides of a point P_3 . In this case, since the points a_2 and b_2 lie on an elliptic line whose focuses are selected at the points P_2 and P_0' and which passes the point P_3 , the ultrasonic waves thus reflected at the reflecting surfaces D_3 are both centered on the point P_0' . This embodiment is small in transmission loss and capable of providing an exactly defined delay time and excellent characteristics, as is the case with the foregoing embodiments.

FIG. 20 shows a twentieth embodiment of this invention, in which parts corresponding to those in FIG. 19 are identified by the same reference numerals and

characters and no detailed description will be repeated. This embodiment has four reflecting surfaces D_1 to D_4 . The reflecting surface D_1 extends along an elliptic line whose focuses are selected at the points P_0 and P_2 and which passes the point P_1 ; the reflecting surfaces D_2 and D_3 lie in planes extending along straight lines; and the reflecting surface D_4 extends along an elliptic line whose focuses are at the point P_2-1 and P_0' and which passes a point P_4 .

With such an arrangement of the twentieth embodiment, it is possible to obtain the same excellent results as those obtainable with the embodiment of FIG. 19.

FIG. 21 illustrates a twenty-first embodiment of this invention which employs five reflecting surfaces D_1 to D_5 . In the present embodiment, the reflecting surfaces D_1 , D_3 and D_5 lie in planes extending along straight lines and those D_2 and D_4 extend along elliptic lines. This embodiment also provides the same results as those obtainable with the foregoing examples.

FIG. 22 shows a twenty-second embodiment of this invention in which three linear reflecting surfaces D_2 , D_3 and D_4 and elliptic ones D_1 and D_5 are sequentially arranged in order of D_1 , D_2 , ... D_5 from the side of the input transducer 2. This embodiment, though not described in detail, also provides the same results as those obtainable with the foregoing examples.

FIG. 23 illustrates another embodiment of this invention which employs four linear reflecting surfaces D_1 , D_2 , D_4 and D_6 and two elliptic reflecting surfaces D_3 and D_5 . This embodiment, though not described in detail, also provides the same results as those obtainable with the foregoing examples.

FIG. 24 shows another embodiment of this invention employing two linear reflecting surfaces D_2 and D_4 and three elliptic reflecting surfaces D_1 , D_3 and D_5 , FIG. 25 another embodiment employing four linear reflecting surfaces D_1 , D_3 , D_5 and D_7 and three elliptic reflecting surfaces D_2 , D_4 and D_6 , and FIG. 26 another embodiment employing five linear reflecting surfaces D_2 , D_4 , D_5 , D_6 and D_8 and four elliptic reflecting surfaces D_1 , D_3 , D_7 and D_9 . Though not described in detail, these embodiments also provide the same results as those obtainable with the foregoing examples.

Where more than three reflecting surfaces are provided as in the embodiments of FIGS. 19 to 26, if the number of the reflecting surfaces is taken as n and if the reflecting surfaces are sequentially taken as D_1 , D_2 , ... D_n , the reflecting surfaces (taken as D_{e1} , D_{e2} , ... D_{eq}) except q 's ones (q being an integer greater than 3) sequentially selected from the reflecting surfaces D_1 to D_n are each formed straight (in the case of $n = 3$, such straight-line surface is not present) and the reflecting surfaces D_{e2} , D_{e4} , ... D_{eq-1} are also straight-line surfaces respectively. If the central point on the mounting side surface 4 is taken as g_0 , if the central points on the reflecting surfaces D_{e1} , D_{e2} , ... D_{eq} are taken as g_1 , g_2 , ... g_q respectively and if the central point on the mounting side surface 4' is taken as $g_{(q+1)}$, the reflecting surface D_{ei} ($i = 1, 3, \dots, q$) extends along an elliptic line whose focuses are at the central point g_{i-1} or its equivalent point and the central point g_{i+1} or its equivalent point when viewed from the central point g_i .

The foregoing description has been made in connection with the case where the solid plate 1 has two transducer mounting side surfaces 4 and 4' and input and output electro-mechanical transducers 2 and 2' are mounted thereon. This is limited to the case where the

ultrasonic wave is regarded as being emitted from the effective central point of the input transducer 2 as in the embodiments of FIGS. 1 to 9 and 19 to 26 but it is also possible to use the transducer mounting side surface 4' as a reflecting surface and cause the transducer on the mounting side surface 4 to serve as a combined input and output transducer, by which the resulting delay time can be lengthened twice that obtainable with the foregoing embodiment and the same results as those described in the foregoing can be obtained.

The foregoing embodiments should be construed as merely illustrative of this invention and many modifications and variations may be effected without departing from the scope of the novel concepts of this invention.

What is claimed is:

1. An ultrasonic delay line comprising:
  - a. a solid plate for propagation of ultrasonic mechanical energy therethrough, and
  - b. first and second electro-mechanical transducers for converting electrical energy into ultrasonic mechanical energy or vice versa,
  - c. the solid plate having parallel, opposing first and second major surfaces, first and second transducer mounting side surfaces normal to the first and second major surfaces and extending along a straight line when viewed from the sides of the first and second major surfaces, and n reflecting surfaces D_1 to D_n (n being an integer) normal to the first and second major surfaces,
  - d.
    - i. the first electro-mechanical transducer being mounted on the first transducer mounting side surface and polarized parallel to the first and second major surfaces and the first mounting side surface,
    - ii. the second electro-mechanical transducer being mounted on the second transducer mounting side surface and polarized parallel to the first and second major surfaces and the second mounting side surface,
    - e. the first and second mounting side surfaces and the reflecting surfaces D_1 to D_n being arranged relative to one other in such a manner that the ultrasonic wave, emitted from the first electro-mechanical transducer and normal to the central point on the first mounting side surface corresponding to the effective central point on the first electro-mechanical transducer viewed from the sides of the first and second major surfaces, propagates in the solid plate and is successively reflected at central points P_1 , P_2 , ... P_n on the reflecting surfaces D_1 , D_2 , ... D_n viewed from the sides of the first and second major surfaces and strikes the second electro-mechanical transducer normal to the second mounting side surface corresponding to the effective central point on the second electro-mechanical transducer, viewed from the sides of the first and second major surfaces,
    - f.
      - i. each of the reflecting surfaces D_1 to D_n except one of them D_e lying in a plane extending along a straight line passing the central point on that reflecting surface viewed from the sides of the first and second major surfaces (in the case of $n = 1$, any of such reflecting surfaces being not present), and

ii. said reflecting surface D_e extending along a elliptic line whose focuses are effectively located at the central points on the first and second mounting side surfaces viewed from the central point of the elliptic reflecting surface D_e viewed from the 5 sides of the first and second major surfaces or at equivalent central points to them and which passes the central point on the said elliptic reflecting surface D_e , to focus the ultrasonic wave from one transducer onto the other transducer. 10

2. An ultrasonic delay line comprising:

- a. a solid plate propagation of ultrasonic mechanical energy therethrough, and
- b. an electro-mechanical transducer for converting 15 electrical energy into ultrasonic mechanical energy or vice versa,
- c. the solid plate having parallel, opposing first and second major surfaces, a transducer mounting side surface normal to the first and second major surfaces and extending along a straight line when viewed from the sides of the first and second major surfaces, and n reflecting surfaces D_1 to D_n normal to the first and second major surfaces, 20
- d. the electro-mechanical transducer being mounted 25 on the transducer mounting side surface and polarized parallel to the first and second major surfaces and the mounting side surface,
- e. the mounting side surface and the reflecting surfaces D_1 to D_n being arranged relative to one other 30 in such a manner that the ultrasonic wave, emitted from the first electro-mechanical transducer normal to the first mounting side surface corresponding to the effective central point on the electro-mechanical transducer viewed from the sides of the first and second major surfaces, propagates in the solid plate and is successively reflected at central 35 points $P_1, P_2, \dots, P_n$ on the reflecting surfaces $D_1, D_2, \dots, D_n$ viewed from the sides of the first and second major surfaces and then successively reflected 40 again at the central points $P_{n-1}, P_{n-2}, \dots, P_1$ on the reflecting surfaces $D_{n-1}, D_{n-2}, \dots, D_1$ and strike the electro-mechanical transducer,
- f.
  - i. each of the reflecting surfaces D_1 to D_n except 45 one of them D_e lying in a plane extending along a straight line passing the central point on that reflecting surface viewed from the sides of the first and second major surfaces, and
  - ii. said reflecting surface D_e extending along an elliptic line whose focuses are selected at the central points on the mounting side surface and reflecting surface D_n viewed from the central point on the reflecting surface D_e viewed from the 50 sides of the first and second major surfaces or at equivalent central points to them and which passes the central point on the reflecting surface D_e . 55
- 3. An ultrasonic delay line comprising:
- a. a solid plate for propagation of ultrasonic mechanical energy therethrough, and
- b. first and second electro-mechanical transducers for converting electrical energy into ultrasonic mechanical energy or vice versa,
- c. the solid plate having parallel, opposing first and second major surfaces, first and second transducer mounting side surfaces normal to the first and sec- 60
- 65

ond major surfaces and extending along a straight line when viewed from the sides of the first and second major surfaces, and n reflecting surfaces D_1 to D_n normal to the first and second major surfaces,

d

- i. the first electro-mechanical transducer being mounted on the first transducer mounting side surface and polarized parallel to the first and second major surfaces and the first mounting side surface,
- ii. the second electro-mechanical transducer being mounted on the second transducer mounting side surface and polarized parallel to the first and second major surfaces and the second mounting side surface,
- e. the first and second mounting side surfaces and the reflecting surfaces D_1 to D_n being arranged relative to one other in such a manner that the ultrasonic waves, emitted from the first electro-mechanical transducer normal to the central and first and second side points on the first mounting side surface corresponding to the effective central and both side points on the first electro-mechanical transducer viewed from the sides of the first and second major surfaces, respectively propagate in the solid plate along paths of the same length and are successively reflected at central points $P_1, P_2, \dots, P_n$ and first and second side points c_1 and d_1, c_2 and $d_2, \dots, c_n$ and d_n on the both sides thereof on the reflecting surfaces $D_1, D_2, \dots, D_n$ viewed from the sides of the first and second major surfaces and strike the second electro-mechanical transducer perpendicularly passing the central point and first and second side points on the second mounting side surface respectively corresponding to the effective central and both side points on the second electro-mechanical transducer, viewed from the sides of the first and second major surfaces,
- f.
  - i. each of the reflecting surfaces D_1 to D_n except one of them D_e lying in a plane extending along a straight line passing the central point on that reflecting surface viewed from the sides of the first and second major surface (in the case of $n = 1$, any of such reflecting surfaces being not present),
  - ii. said reflecting surface D_e comprising a linear surface area extending along a straight line connecting the first and second side points on the reflecting surface and first and second elliptic surface areas continuously extending outwardly of the linear surface area, viewed from the sides of the first and second major surfaces,
  - iii. the first elliptic surface area extending along a first elliptic line whose focuses are at the first side points on the first and second mounting side surfaces viewed from the first side point on the linear surface area or their equivalent side points and which starts from the first side point on the linear surface area, and
  - iv. the second elliptic surface area lying in a plane extending along a second elliptic line whose focuses are at the second side points on the first and second mounting side surfaces viewed from the second side point on the linear surface area or their equivalent side points and which starts

from the second side point on the linear surface area.

4. An ultrasonic delay line comprising:

- a. a solid plate for propagation of ultrasonic mechanical energy therethrough, and
- b. an electro-mechanical transducer for converting electrical energy into ultrasonic mechanical energy or vice versa,
- c. the solid plate having parallel, opposing first and second major surfaces, a transducer mounting side surface normal to the first and second major surfaces and extending along a straight line when viewed from the sides of the first and second major surfaces, and n reflecting surfaces D_1 to D_n normal to the first and second major surfaces,
- d. the electro-mechanical transducer being mounted on the transducer mounting side surface and polarized parallel to the first and second major surfaces and the mounting side surface,
- e. the mounting side surface and the reflecting surfaces D_1 to D_n being arranged relative to one other in such a manner that the ultrasonic waves, emitted from the first electro-mechanical transducer normal to the central and first and second side points on the first mounting side surface respectively corresponding to the effective central and both side points on the electro-mechanical transducer viewed from the sides of the first and second major surfaces, respectively propagates in the solid plate along paths of the same length and are successively reflected at central points $P_1, P_2, \dots, P_n$ and first and second side points $c_1, c_2, \dots, c_n$ and $d_1, d_2, \dots, d_n$ on the both sides thereof on the reflecting surfaces $D_1, D_2, \dots, D_n$ viewed from the sides of the first and second major surfaces and then successively reflected again at the central points $P_{n-1}, P_{n-2}, \dots, P_1$ and the first and second side points $c_{n-1}, c_{n-2}, \dots, c_1$ and $d_{n-1}, d_{n-2}, \dots, d_1$ respectively on the both sides thereof and strike the electro-mechanical transducer,
- f.
  - i. each of the reflecting surfaces D_1 to D_n except one of them lying in a plane extending along a straight line passing the central point on that reflecting surface viewed from the sides of the first and second major surfaces
  - ii. the reflecting surface D_e comprising a linear surface area extending along a straight line connecting the first and second side points on the reflecting surfaces and first and second elliptic surface areas continuously extending outwardly of the linear surface area, viewed from the sides of the first and second major surfaces,
  - iii. the first elliptic surface area extending along a first elliptic line whose focuses are at the first side points on the first and second mounting side surfaces viewed from the first side points on the linear surface area or their equivalent side points and which starts from the first side point on the linear surface area, and
  - iv. the second elliptic surface area extending along a second elliptic line whose focuses are at the second side points on the first and second mounting side surfaces viewed from the second side point on the linear surface area or their equivalent side points and which starts from the second side point on the linear surface area.

5. An ultrasonic delay line comprising:

- a. a solid plate for propagation of ultrasonic mechanical energy therethrough, and
- b. first and second electro-mechanical transducers for converting electrical energy into ultrasonic mechanical energy or vice versa,
- c. the solid plate having parallel, opposing first and second major surfaces, first and second transducer mounting side surfaces normal to the first and second major surfaces and extending along a straight line when viewed from the sides of the first and second major surfaces, and n reflecting surfaces D_1 to D_n normal to the first and second major surfaces,
- d.
  - i. the first electro-mechanical transducer being mounted on the first transducer mounting side surface and polarized parallel to the first and second major surfaces and the first mounting side surface,
  - ii. the second electro-mechanical transducer being mounted on the second transducer mounting side surface and polarized parallel to the first and second major surfaces and the second mounting side surface,
- e. the first and second mounting side surfaces and the reflecting surfaces D_1 to D_n being arranged relative to one other in such a manner that the ultrasonic wave, emitted from the first electro-mechanical transducer and normal to the central point on the first mounting side surface corresponding to the effective central point on the first electro-mechanical transducer viewed from the sides of the first and second major surfaces, propagates in the solid plate and is successively reflected at central points $P_1, P_2, \dots, P_n$ on the reflecting surfaces $D_1, D_2, \dots, D_n$ viewed from the sides of the first and second major surfaces and strikes the second electro-mechanical transducer perpendicularly passing the central point on the second mounting side surface corresponding to the effective central point on the second electro-mechanical transducer, viewed from the sides of the first and second major surfaces,
- f.
  - i. each of the reflecting surfaces except q reflecting surfaces $D_{e1}, D_{e2}, \dots, D_{eq}$ respectively sequentially selected from those D_1 to D_n lying in a plane extending along a straight line passing the central point on that reflecting surface, viewed from the sides of the first and second major surfaces (in the case of $n = q$, such linear reflecting surfaces are not present),
  - ii. each of the reflecting surfaces $D_{e2}, D_{e4}, \dots, D_{e(q-1)}$ lying in a plane extending along a straight line passing the central point on that reflecting surface, viewed from the sides of the first and second major surfaces, and
  - iii. the reflecting surface D_{e1} ($i = 1, 3, \dots, q$), if the central point on the mounting side surface is taken as g_0 , if the central points on the reflecting surfaces $D_{e1}, D_{e2}, \dots, D_{eq}$ are taken as $g_1, g_2, \dots, g_q$ respectively and if the central point on the second mounting side surface is taken as $g_{(q+1)}$, lying in a plane extending along an elliptic line whose focuses are at the central points g_{i-1} and g_{i+1} viewed from the central point g_i viewed from the

- sides of the first and second major surfaces and which passes the central point g_i .
6. An ultrasonic delay line comprising:
- a solid plate for propagation of ultrasonic mechanical energy therethrough, and
  - b. an electro-mechanical transducer for converting electrical energy into ultrasonic mechanical energy or vice versa,
  - c. the solid plate having parallel, opposing first and second major surfaces, a transducer mounting side surface normal to the first and second major surfaces and extending along a straight line when viewed from the sides of the first and second major surfaces, and n reflecting surfaces D_1 to D_n normal to the first and second major surfaces,
  - d. the electro-mechanical transducer being mounted on the transducer mounting side surface and polarized parallel to the first and second major surfaces and the mounting side surface,
  - e. the mounting side surface and the reflecting surfaces D_1 to D_n being arranged relative to one other in such a manner that the ultrasonic wave, emitted from the electro-mechanical transducer normal to the central point on the mounting side surface corresponding to the effective central point on the electro-mechanical transducer viewed from the sides of the first and second major surfaces, propagates in the solid plate and is successively reflected at central points $P_1, P_2, \dots, P_n$ on the reflecting surfaces $D_1, D_2, \dots, D_n$ viewed from the sides of the first and second major surfaces and then successively reflected again at the central points $P_{n-1}, P_{n-2}, \dots, P_1$ on the reflecting surfaces $D_{n-1}, D_{n-2}, \dots, D_1$ and strikes the electro-mechanical transducer,
  - f.
- i. each of the reflecting surfaces except q reflecting surfaces (taken as $D_{e1}, D_{e2}, \dots, D_{eq}$ respectively sequentially selected from those D_1 to D_{n-1} lying in a plane extending along a straight line passing the central point on the reflecting surface, viewed from the sides of the first and second major surfaces,
- ii. each of the reflecting surfaces $D_{e2}, D_{e4}, \dots, D_{e(q-1)}$ lying in a plane extending along a straight line passing the central point on that reflecting surface, viewed from the sides of the first and second major surfaces, and
- iii. the reflecting surface D_{ei} ($i = 1, 3, \dots, q$), if the central point on the mounting side surface is taken as g_0 , if the central points on the reflecting

surfaces $D_{e1}, D_{e2}, \dots, D_{eq}$ are taken as $g_1, g_2, \dots, g_q$ respectively and if the central point P_n on the reflecting surface is taken as $g_{(q+1)}$, extending along an elliptic line whose focuses are at the central points g_{i-1} and g_{i+1} viewed from the central point g_i viewed from the sides of the first and second major surfaces and which passes the central point g_i .

7. An ultrasonic delay line according to claim 1

10 wherein the distance between the first and second major surfaces is 0.5 to 5 times the wavelength of the ultrasonic mechanical energy wave.

8. An ultrasonic delay line according to claim 2,

15 wherein the distance between the first and second major surfaces is 0.5 to 5 times the wave length of the ultrasonic mechanical energy wave.

9. An ultrasonic delay line according to claim 3, wherein the distance between the first and second major surfaces is 0.5 to 5 times the wavelength of the ultrasonic mechanical energy wave.

10. An ultrasonic delay line according to claim 4, wherein the distance between the first and second major surfaces is 0.5 to 5 times the wavelength of the ultrasonic mechanical energy wave.

11. An ultrasonic delay line according to claim 5, wherein the distance between the first and second major surfaces is 0.5 to 5 times the wavelength of the ultrasonic mechanical energy wave.

12. An ultrasonic delay line according to claim 6, wherein the distance between the first and second major surfaces is 0.5 to 5 times the wavelength of the ultrasonic mechanical energy wave.

13. An ultrasonic delay line according to claim 1 wherein the value n is an odd number larger than 3 and the elliptic reflecting surface is $n + 1/2$ th from the first transducer mounting side surface.

14. An ultrasonic delay line according to claim 2, wherein the value n is an odd number larger than 3 and the elliptic reflecting surface is $n + 1/2$ th from the first transducer mounting side surface.

15. An ultrasonic delay line according to claim 3, wherein the value n is an odd number larger than 3 and the elliptic reflecting surface is $n + 1/2$ th from the first transducer mounting side surface.

16. An ultrasonic delay line according to claim 4, wherein the value n is an odd number larger than 3 and the elliptic reflecting surface is $n + 1/2$ th from the first transducer mounting side surface.
